US00D870711S

(12) **United States Design Patent** (10) **Patent No.:** **US D870,711 S**
(45) **Date of Patent:** **** Dec. 24, 2019**

(54) **HEADPHONE**

- (71) Applicant: **Harman International Industries, Incorporated**, Northridge, CA (US)
(72) Inventors: **Effrosini A. Karayiannis**, St. Louis, MO (US); **Hyo Jin Kim**, Shenzhen (CN); **Derek Campbell**, Baltimore, MD (US)
(73) Assignee: **Harman International Industries, Incorporated**, Northridge, CA (US)
(**) Term: **15 Years**
(21) Appl. No.: **29/674,293**
(22) Filed: **Dec. 20, 2018**

Related U.S. Application Data

- (63) Continuation-in-part of application No. 29/631,217, filed on Dec. 28, 2017.

(57) **CLAIM**

The ornamental design for a headphone, as shown and described.

DESCRIPTION

FIG. 1 is a perspective view of a headphone showing the new design in a first embodiment;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof;

FIG. 7 is a bottom view thereof;

FIG. 8 is a perspective view of the headphone in a second embodiment, illustrating a mirror image of the headphone of FIGS. 1-7;

FIG. 9 is a front elevational view thereof;

FIG. 10 is a rear elevational view thereof;

FIG. 11 is a side elevational view thereof;

FIG. 12 is an opposite side elevational view thereof;

FIG. 13 is a top view thereof; and,

FIG. 14 is a bottom view thereof.

The broken lines shown in the drawings depict portions of the headphone that form no part of the claimed design.

1 Claim, 14 Drawing Sheets
